UNITED STATES PATENT OFFICE.

ARCHIE A. MACCALLUM, OF MAGOG, CANADA.

ENGRAVING-MACHINE ATTACHMENT.

SPECIFICATION forming part of Letters Patent No. 635,895, dated October 31, 1899.

Application filed May 4, 1899. Serial No. 715,597. (No model.)

To all whom it may concern:

Be it known that I, ARCHIE A. MACCALLUM, a subject of the Queen of Great Britain, residing at Magog, in the Province of Quebec and Dominion of Canada, have invented certain new and useful Improvements in Attachments for Pantograph Engraving-Machines; and I do declare the following to be a full, clear, and exact description of the invention, such as will enable others skilled in the art to which it appertains to make and use the same.

My invention relates to an attachment for pantograph engraving-machines, and more particularly to that class in which the pattern or design is duplicated on the copper printing-cylinder by a series of diamond points fixed in the free ends of a corresponding series of individual lever-arms simultaneously operated by a treadle and which is generally known to the trade as the "Hope pantograph engraving-machine," and the object is to improve the construction and increase the efficiency of the machine.

To this end the invention consists in certain features of construction and combination of parts, which will be hereinafter more fully described and claimed.

In the accompanying drawings, the same reference characters indicate the same parts of the invention.

Figure 1 is a perspective view of the upper part of a pantograph engraving-machine with my improvement attached thereto. Fig. 2 is a detail view of the attachment removed from the machine.

1 denotes a copper cylinder upon which the designs are traced by the diamonds 2 2, fixed in the free ends of the levers 3 3, fulcrumed on the bar 4, and 5 denotes the curved bar 40 which extends across the path of the rear ends of the levers and which is connected to the treadle by a rod 6, so that when the treadle is pressed down the diamond points will be

brought into contact with the cylinder, and when the treadle is released the points will be 45 raised clear of the cylinder.

Provision is made for rotating the cylinder forward and backward and also for moving the bar 4 longitudinally, thereby moving the diamond points laterally to produce the 50 proper design on the cylinder.

Heretofore the end levers 3' 3' when moved beyond the end of the cylinder would drop below the face of the cylinder and in moving back again would come in contact with the 55 end of the cylinder and be broken off or bent out of true, and in order to overcome this objection I have provided the shoe 7, which is adjustably secured to the curved bar 5, so as to project across the rear ends of the levers 3' 60 3' and support them when their points have been moved beyond the ends of the cylinder.

The accompanying drawings show my invention in the best form now known to me; but many changes in the details might be 65 made within the skill of a good mechanic without departing from the spirit of my invention as set forth in the claim at the end of this specification.

Having thus fully described my invention, 70 what I claim, and desire to secure by Letters Patent of the United States, is—

In a machine of the class described, the combination with the end levers, of the curved bar 5 and the shoes 7 7 mounted on said bar 75 and projecting into the path of the rear ends of said levers, substantially as and for the purpose set forth.

In testimony whereof I have hereunto set my hand in presence of two subscribing witnesses.

ARCHIE A. MACCALLUM.

Witnesses:

WILLIAM KINCAID,
WM. MACCALLUM.
